CHAIR

Edward L. Koenig, Wilmette, Ill.

Application June 28, 1943, Serial No. 492,477

2 Claims. (Cl. 155—94)

This invention relates to a chair.

More particularly, this invention relates to a so-called posture chair of the general character commonly employed in business and professional offices and like places by stenographers, secretaries, and other persons.

As commonly made heretofore, so-called posture chairs have been made in part of wood but have embodied a substantial part and quantity of metal, including a vertically extending and adjustable seat-supporting screw member, and by reason of the prevailing shortage of materials, it has now become difficult, if not impossible, to manufacture such posture chairs in the structures and from the materials heretofore employed.

Accordingly, an object of the invention is to provide a new and improved posture chair which may be made of available materials, that is to say, largely of wood, and with a minimum number of metal parts.

Another object of the invention is to embody in the new posture chair a novel construction for adjusting the seat unit and the back rest unit thereof to the desired vertical height and for retaining the seat unit and the back rest unit at a preselected vertical height.

A further object of the invention is to construct and arrange the new posture chair in such a manner that the seat unit and the back rest unit thereof may be securely and firmly held in any selected adjusted position and at any desired vertical height without the use of the vertically extending adjustable seat-supporting metal screw and associated parts heretofore employed in posture chairs.

An additional object of the invention is to construct and arrange the new posture chair so that the same embodies a minimum of parts and so that it may, therefore, be made relatively economically and inexpensively.

A further object of the invention is to construct and arrange the new posture chair in such a manner that the back rest unit thereof may be adjustably mounted, in a novel manner, and by novel means, upon and relative to the seat unit of the new chair.

Still another object of the invention is to construct and arrange the new posture chair in such a manner that the vertically extending and vertically adjustable seat-supporting post may be made in various cross sectional forms, that is, so that it may be square or rectangular, or cylindrical, or the like in cross sectional form.

An additional object of the present invention is to construct and arrange the new posture chair in such a manner that the back rest unit em-

bodied therein may be readily adjusted to a selected height, relative to the seat, and may be clamped into a firm rigid association with the seat unit.

Other and further objects of the present invention will be apparent from the following description and claims and will be understood by reference to the accompanying drawing which, by way of illustration, shows preferred embodiments and the principles thereof and what I now consider to be the best mode in which I have contemplated applying those principles. Other embodiments of the invention embodying the same or equivalent principles may be used and structural changes may be made as desired by those skilled in the art without departing from the present invention and the purview of the appended claims.

In the drawing,

Fig. 1 is a front elevational view of the new posture chair embodying a preferred form of the present invention;

Fig. 2 is a side elevational view of the same;

Fig. 3 is a horizontal sectional plan view on line 3—3 in Fig. 1;

Fig. 4 is a fragmentary detail view, partly in section and partly in elevation, showing the manner in which the clamping bolts engage in the notched peripheral edge portions of the vertically extending and adjustable seat-supporting post in the preferred embodiment of the new posture chair which is shown in Figs. 1 to 6, inclusive, of the drawing;

Fig. 5 is a fragmentary rear elevational view, on line 5—5 in Fig. 2, showing a preferred form of the novel means embodied in the new chair for adjusting the back rest unit vertically upon and relative to the seat unit embodied in the new chair;

Fig. 6 is a sectional top plan view, on line 6—6 in Fig. 2, showing a preferred embodiment of the means for adjustably mounting the back rest unit laterally or horizontally upon and relative to the seat of the new posture chair; and

Fig. 7 is a fragmentary sectional plan view showing a modification of one feature of the new posture chair and in which the vertically extending seat-supporting post is cylindrical in form and is provided with vertically spaced annular grooves in which the clamping bolts may be engaged for holding the seat unit and the back rest unit at a preselected vertical height.

A typical embodiment of the new posture chair is shown in Figs. 1 to 6, inclusive, of the drawing and comprises, in general, a pedestal or supporting unit 10, a vertically extending and vertically

adjustable supporting post 11, a seat unit 12 carried thereby, and a back rest unit 13 which is carried by and which is adjustably mounted upon the seat unit 12.

The pedestal or supporting base 10 comprises a pair of angularly extending front legs 14, interconnected by a cross brace 16, and a pair of angularly extending rear legs 15 interconnected by a cross brace 17.

The supporting base 10 also includes a clamping block 18 which is rigidly mounted upon the upper ends of the two rear legs 15, in any suitable manner, as by means of suitable fastening elements, such as nails, or by means of a suitable adhesive, or the like, and the supporting base 10 also includes a second and similar wooden clamping block 19 which is rigidly mounted in a similar manner upon the upper ends of the front legs 14.

As shown in Fig. 3, the clamping blocks 18 and 19 are interconnected by a pair of dowel pins 20 which are fitted into openings 21 provided therefor in the front clamping block 19 and into similar openings 22 provided in the rear clamping block 18 and aligned with the openings 21 in the front clamping block 19. One of the dowel pins 20 is preferably made fast in the opening 21 provided therefor in the front clamping block 19, as by means of a suitable adhesive, and this dowel pin is slidable in the opening 22 provided therefor in the rear clamping block 18. The other dowel pin 20 is made fast in the opening 22 provided therefor in the rear clamping block 18, as by means of a suitable adhesive, and this dowel pin is slidable in the opening 21 provided therefor in the front clamping block 19. In this manner the two clamping blocks 18 and 19 are maintained in proper alignment with each other while being allowed a limited amount of play or movement relative to each other upon the dowel pins 20.

As shown in Fig. 3 of the drawing, the inner or rear edge of the front clamping block 19 is provided with a centrally arranged recess 23 and the inner or front edge of the rear clamping block 18 is provided with a similarly arranged and complementary recess 24 and, as shown in the drawing, the vertically extending and adjustable supporting post 11 extends through, and fits in, the two complementary central recesses 23 and 24 of the front and rear clamping blocks 19 and 18, respectively.

The vertically extending and adjustable supporting post 11 is shown in Figs. 1 to 6, inclusive, of the drawing as being square or rectangular in cross section and this post 11 is provided at each of its corners with a row of vertically spaced indentations or recesses in the form of notches 25. It will be noted, in this connection, that the notches 25 are arranged in both vertical and horizontal rows, for reasons which will be made apparent presently.

The front clamping block 19 is provided with a pair of spaced horizontally extending openings 26 and the rear clamping block 18 is provided with a similar pair of spaced horizontally extending openings 27 which are aligned with the openings 26 in the front clamping block 19, as best shown in Fig. 3, and a pair of clamping bolts 28 are extended through the pairs of aligned openings 26 and 27. Each of these clamping bolts 28 has a clamping wing nut 29 mounted upon its threaded rear end portion, and rearwardly of the rear clamping block 19, as shown in the drawing.

A wooden block 30 is attached to the under side of the seat 12 and this block 30 is also attached, in any suitable manner, to the upper end portion of the vertically extending and adjustable supporting post 11. The block 30 includes an offset or cut-away portion 30a (Fig. 2) providing a rear portion 30b of reduced thickness and a pair of spaced vertically extending bolts 32 are anchored in the rear portion of part 30b of the block 30, as shown in Figs. 2 and 6.

The new chair includes a wooden back rest supporting slide block 33 and this slide block 33 has a reduced portion 33a which projects into the recessed portion 30a of the block 30.

The reduced portion 30b of the block 30 is provided with a pair of spaced horizontally extending and parallel slots 31 (Fig. 6) and, as shown, one of the vertically extending bolts 32, carried by the reduced portion 30b of the block 30, extends into and works in each of the slots 31, and a wing nut 34 is mounted on the threaded end portion of each of the bolts 32 below the block 33.

The back rest unit 13 of the new posture chair includes an arched back rest supporting post 35 and a curved back rest 36 is pivotally mounted, as at 37, upon the upper end portion of the back rest supporting post 35.

The rear end portion of the slide block is provided with a notched portion 38 (Fig. 6) and the lower end portion of the back rest post 35 extends into this notched portion 38 of the slide block 33, as shown in Fig. 6.

As shown in Figs. 5 and 6, the lower end portion of the back rest supporting post 35 is provided with a vertically extending slot 39 and a clamping bolt 40, which is anchored in the slide block 33, projects into and works in the slot 39, this clamping bolt 40 having a threaded rear end portion on which a clamping wing nut 41 is mounted.

As shown in Figs. 2 and 6 of the drawing, the upper surface of the reduced portion 33a of the slide block 33 is provided with a centrally arranged horizontally extending guide rib 42 and the lower surface of the reduced portion 30b of the block 30 is provided with a corresponding groove 43.

It will be noted that when the parts of the new posture chair are in assembled position, as shown in the drawing, each of the clamping bolts 28 projects into and engages in one of the recesses or notches 25 in the vertically extending and adjustable supporting post 11 and that the clamping bolts 28 are maintained in clamping engagement in the particular notches 25, in which they are engaged, by the combined action of the clamping blocks 18 and 19 and the clamping units 29 on the clamping bolts 28 while, at the same time, the gripping action of the clamping blocks 18 and 19 upon the post 11 helps to maintain the latter and the seat unit 12 and the back rest 13 at the desired height. In this manner the seat unit 12 and the back rest unit 13 are maintained at a desired and selected vertical height and these parts cooperate with the supporting base or pedestal 10 to form a firm, rigid chair.

However, if and when it is desired to adjust the seat unit 12 and the back rest unit 13 vertically upon and relative to the supporting unit 10, this may be accomplished by removing the clamping wing nuts 29 from the threaded rear end portions of the clamping bolts 28, sliding the clamping bolts 28 forwardly in the aligned openings 26 and 27 provided therefor in the front

and rear clamping blocks 18 and 19, respectively, so that they pass out of engagement with or in the notched portions 25 of the supporting post 11. The vertically extending supporting post 11 and the seat unit 12 and the back rest unit 13 carried thereby may then be adjusted to the desired vertical height, whereupon the clamping bolts 28 may again be slid back into position in the openings 26 and 27 provided therefor in the front and rear clamping blocks 18 and 19, respectively. The clamping bolts 28 will then engage with another selected pair of the notched portions 25 of the vertically extending supporting post 11, whereupon clamping wing nuts 29 on the bolts 28 may then be reapplied in position of use upon the threaded rear end portions of the clamping bolts 28 and tightened thereon. In this manner the centrally recessed inner edge portions 23 and 24 of the front and rear clamping blocks 18 and 19, respectively, are clampingly engaged with the vertically extending supporting post 11 while, at the same time, the horizontally extending clamping bolts 28 are clampingly engaged in the selected notched portion 25 of the vertically extending supporting post 11, thus maintaining the seat unit 12 and the back rest unit 13 carried thereby at the desired adjusted height.

As shown in Fig. 3, the clamping blocks 18 and 19 are initially spaced slightly from each other. However, if and when wear occurs in the notched portions 24 and 23 of the clamping blocks 18 and 19, respectively, or in the notched portions 25 of the vertically extending post 11, such wear may be compensated for by tightening the clamping blocks 18 and 19 closer together upon the dowel pins 20 and the clamping bolt 28 by tightening the clamping nuts 29 upon the clamping bolts 28.

Horizontal adjustment of the back rest unit 13 upon and relative to the seat unit 12 may be readily accomplished by loosening the clamping nuts 34 on the vertically extending bolts 32 and then moving the slide block 33 in the recessed or cut-away portion 30a of the block 30. During this adjustment the vertically extending bolts 32 slide in the horizontally extending slots 31 which are formed in the slide block 33, and the movement of the slide block 33 upon and relative to the reduced portion 30b of the block 30 is guided by the horizontally extending rib 42 which works in the correspondingly shaped groove 43 in the reduced portion 30b of the block 30.

Accordingly, when the desired adjustment has been secured the reduced portion 33a of the slide block 33 may be clampingly engaged with the reduced portion 30b of the block 30 by tightening the clamping nuts 34 on the bolts 32, thus securing the desired horizontal adjustment of the back rest unit 13 upon and relative to the seat unit 12.

The desired vertical height of the back supporting post 35 and of the back rest 36 carried thereby upon and relative to the slide block 33, which carries these parts, may be accomplished by loosening the clamping nut 41 and adjusting the back rest supporting post 35 to the desired height and then again tightening the clamping nut 41 on the bolt 40. During this adjustment of the back rest supporting post 35 and of the back rest 36 carried thereby the bolt 40 works in the vertical seat 39 which is formed in the lower portion of the back rest post 35.

While the vertically extending and adjustable supporting post 11 has been shown as being square in cross section, and as being provided with hori-

zontally and vertically aligned rows of notches 25, formed in its corner portions, it will be understood that the cross sectional shape or form of the vertically extending and adjustable supporting post 11 may be varied and that within the scope of the invention the post 11 may be made in various geometrical cross sectional shape or forms such, for example, as round or cylindrical. Such a modification of this feature of the invention is fragmentarily illustrated in Fig. 7, wherein the vertically extending and adjustable supporting post 11a is shown as being cylindrical in cross sectional shape or form and as being provided with recesses or indentations in the form of vertically spaced annular grooves 25a which are adapted for the selective reception of clamping bolts 28a, which are similar to the bolts 28.

In this modification of the aforesaid feature of the invention the inner edge portions of the clamping blocks 18a and 19a are provided with centrally arranged recesses 24a and 23a, respectively, for the reception of the cylindrical vertically extending and adjustable supporting post 11a.

Except as thus indicated, the modified form of the invention which is fragmentarily illustrated in Fig. 7 is the same in construction and use as the form of the invention shown in Figs. 1 to 6, inclusive, and may be embodied in the new chair 30 without additional changes other than those shown in Fig. 7 and hereinbefore described.

It will be noted that one of the novel features of the new chair is that the front and rear supporting legs 14 and 15 and their interconnecting horizontal cross braces 16 and 17 and the clamping blocks 18 and 19 carried thereby form a single unitary structure which adds strength and rigidity to the chair and is preferable to an arrangement in which the clamping blocks 18 and 19 might be mounted upon separable front and rear leg and brace units which would tend to become separated from each other and which would impart lack of rigidity and structural weakness to the resulting chair.

While the major structural parts of the new chair, including the clamping blocks 18 and 19, have been shown as made of solid wood, it will be understood that within the scope and contemplation of the present invention the clamping blocks 18 and 19 and other major structural parts of the new chair may also be made of hollow wood parts, or of metal, or of metals of formed section, or partly of wood and metal, or of other materials, if desired.

It will thus be seen from the foregoing description, considered in conjunction with the accompanying drawing, that the present invention accomplishes its intended objects, and provides a new posture chair having the desirable advantages and characteristics, including those hereinbefore specifically pointed out, and others which are inherent in the invention.

I claim:

1. A chair comprising a supporting base including a supporting leg structure, a vertically extending seat-supporting post having vertically spaced indentations formed in its peripheral surface, a chair seat carried by said vertically extending seat-supporting post at the top thereof, and means carried by said supporting leg structure at the top thereof and cooperating with the said vertically extending seat-supporting post to hold the said vertically extending post and the said chair seat carried thereby at a preselected height relative to said supporting base,

4. said holding means including a plurality of clamping blocks carried by the said supporting leg structure at the top thereof and arranged on opposite sides of the said vertically extending supporting post and clampingly engageable therewith, and manually adjustable clamping elements carried by the said clamping blocks and arranged on opposite sides of the said vertically extending supporting post and releasably engageable in the said indentations in the said supporting post for holding the said clamping blocks in clamping engagement with the said vertically extending support post and for holding the said vertically extending supporting post and the said chair seat carried thereby at a preselected adjusted height relative to the said supporting base.

2. A chair comprising a supporting base including a pair of front supporting legs and a pair of rear supporting legs, a clamping member rigidly attached to said front supporting legs at the top thereof and a separate clamping member rigidly attached to said rear supporting legs at the top thereof, a vertically extending seat-supporting post, a chair seat carried by said vertically extending supporting post at the top thereof, each of said clamping members including an inner edge having a centrally arranged re-

cessed portion formed therein and the said centrally arranged recessed portions cooperating to provide a centrally arranged opening for the reception of the said vertically extending supporting post, and manually operable clamping means carried by the said clamping members for clamping the said centrally arranged recessed portions of the said clamping members in releasable clamping engagement with the said vertically extending supporting post, said vertically extending supporting post having vertically spaced indentations formed in its peripheral surface, said manually operable clamping means comprising a pair of spaced horizontally extending clamping bolts extending through openings provided in said clamping members for the reception thereof, and said clamping bolts being arranged on opposite sides of said vertically extending supporting post, and said clamping bolts being selectively engageable between their ends in the said indentations in the said vertically extending supporting post so as to retain the said vertically extending supporting post and the said chair seat carried thereby at a preselected adjusted height relative to the said supporting base.

EDWARD L. KOENIG.
